UNITED STATES PATENT OFFICE

163,299

ORANGE PEELER OR THE LIKE

David Levin, London, England

Application April 29, 1950, Serial No. 9,576

Term of patent 3½ years

(Cl. D22—3)

To all whom it may concern:

Be it known that I, David Levin, a subject of Great Britain and a resident of the city of London, England, have invented a new, original, and ornamental Design for an Orange Peeler or the like, of which the following is a specification, reference being had to the accompanying drawings, forming a part hereof, in which:

I claim:

The ornamental design for an orange peeler or the like, as shown.

DAVID LEVIN.
